ABSTRACT

A spring clip connector and mounting device for a ceramic glow igniter including a pair of spaced, upstanding, resilient, conductive legs engaging the opposite arcuate surfaces of adjacent and connected semicylindrical end portions of a ceramic loop, one leg being arcuate and the other straight so that they may receive between them and securely support and electrically connect an igniter in which the connected semicylindrical end portions thereof are misaligned.

ELECTRICAL CONNECTOR AND MOUNTING MEANS FOR CERAMIC GLOW IGNITERS

This invention relates to spring clip means for mounting and electrically connecting a ceramic glow igniter to circuit leads, and particularly to such means which is adaptable to securely mount and electrically connect those igniters in which the shape of the end portion to be connected varies considerably.

There are presently at least two commercially available ceramic glow igniters, both of which essentially comprise a loop of conductive ceramic material having adjacent semicylindrical end portions connected by a non-conductive ceramic adhesive to form a generally cylindrical end portion. It has been found that due to the method of manufacturing of at least one of these igniters some misalignment or offset of the semicylindrical end portions frequently occurs. These manufacturing variations while in no way affecting the functioning of the igniter nevertheless present a problem of conveniently mounting and electrically connecting the igniter by conventional spring clip means.

It is an object of the invention, therefore, to provide a simple, spring clip-type, electrical connector and mounting means which will securely mount and electrically connect a ceramic igniter of this kind, whether the end thereof to be connected closely conforms to cylindrical shape or varies substantially therefrom due to misalignment of the semicylindrical ends.

Other objects and advantages will appear from the following description of a preferred form of the invention when read in connection with the accompanying drawing.

In the drawing:

FIG. 1 is a top plan view of a mounting device constructed in accordance with the present invention with a ceramic glow igniter mounted therein;

FIG. 2 is a side elevational view of the mounting device and igniter shown in FIG. 1;

FIG. 3 is an end elevational view of the device shown in FIGS. 1 and 2, taken along line 3—3 of FIG. 2, with the connected end portions of the igniter shown in cross-section;

FIG. 4 is an end elevational view of the mounting device shown alone; and

FIG. 5 is a side elevational view of the mounting device shown alone.

Referring to the various figures of the drawing in more detail, the mounting device generally indicated at 10 comprises a rigid base 12 of electrical insulating material having a hole 13 therein for attaching the base to support means by a bolt or screw. Attached to the base 12 is a pair of horizontally spaced, upstanding legs 14 and 16. Legs 14 and 16 are formed of strips of resilient, electrically conductive metal, and each includes a perforated horizontally formed lower portion 18 lying on the upper surface of base 12. Overlying leg portions 18 is a pair of conductive circuit lead connector elements 20 which together with underlying leg portions 18 are rigidly connected to the base 12 by rivets 22. The elements 20 have upwardly formed free end portions 24 which are perforated to receive the ends of circuit leads.

Upstanding leg 16 has an intermediate straight portion 26 and leg 14 has an intermediate coextending arcuate portion 28 with the concave surface thereof facing leg portion 26. The upper end portions 29 of legs

14 and 16 are flared outwardly to facilitate entry therebetween of the end of an igniter.

A ceramic glow igniter, generally indicated by numeral 30 comprises elongated, coextending, right and left-hand half portions 32 and 34 of a conductive ceramic material such as silicon carbide. Each of the half portions comprises an outer flat portion 36 having deep parallel transverse slots 38 entering alternately from opposite sides thereof to form a long conductor of relatively high resistance, due to its cross-sectional area, and an inner semicylindrical portion 40 of relatively low resistance, the flat sides of which face each other.

The half portions 32 and 34 are joined at their outer ends by a short section 42 of similar conductive material, thereby to form a conductive loop with adjacent semicylindrical end portions. The semicylindrical end portions 40 are connected by a non-conductive ceramic cementing material 44, see FIG. 3. A flat rectangular strip 46 is inserted and cemented in position between portions 40 to form a polarizing fin. The strip 46 is adapted to enter a slot 48 in the base member 12 to limit rotational and axial movement of the igniter in the mounting device. 11

The process of manufacturing the above-described igniter 30 includes the heating thereof to temperatures in the order of 4,000° Fahrenheit to effect, inter alia, the mechanical and electrical connection of half portions 32 and 34 at their outer ends through section 42. During this step in the manufacturing process, it is quite difficult to maintain the precise alignment of the inner ends 40 required to result in an inner end portion closely conforming to a cylinder.

When mounting a ceramic glow igniter of the kind illustrated in the device 10, the inner generally cylindrical end thereof is pressed downward between the resilient legs 14 and 16. Whether the semicylindrical igniter portions 40 are in precise alignment or out of alignment, as indicated in FIG. 3, the arcuate surface of the one igniter portion 40 will slide upon the straight surface 26 of leg 16 until the arcuate surface of the other portion 40 snaps into the arcuate portion 28 of leg 14. The arcuate portion 28 of leg 14 preferably has a radius slightly less than that of the igniter end portion 40. The deflection of the resilient legs and the lateral stress which they exert will not vary substantially therefore, whether the portions 40 are aligned to form a cylinder or are to some considerable degree out of alignment, as indicated in FIG. 3.

50 Igniters with end shapes which are cylindrical or which deviate in various degrees from cylindrical will therefore be uniformly retained in the arcuate leg portion 28 by a sufficient predetermined force, and the opposite end portions 40 of the igniters will be electrically connected to their respective lead connector elements 20 through predetermined areas of contact and pressure. The vertically arranged rectangular strip 46 enters the slot 48 in the base member 12 when the igniter is in the correct position as it is pressed downward into position between legs 14 and 16. The strip 46 when entered in slot 48 limits axial movement of the igniter as well as rotational movement. By forming the arcuate portion 28 of resilient leg 14 with a slightly smaller radius than that of the semicylindrical igniter end portions 40, uniform contact areas are assured for retaining and electrically connecting the igniter.

I claim:

1. A device for supporting and electrically connecting a ceramic glow igniter having adjacent semicylindrical end portions cemented together to form a generally cylindrical igniter end portion and having a polarizing fin positioned between the semicylindrical portions and extending laterally from both sides thereof, the device comprising a base member of electrical insulating material, a pair of resilient electrically conductive legs connected at one end to said base member and extending generally perpendicular therefrom in spaced relationship to the free ends, said legs being spaced so as to be flexed a predetermined amount when the cylindrical end portion of an igniter is pressed between them, thereby to provide a predetermined retention force and electrical contact pressure, one of said legs 15

having an intermediate straight portion adapted to be slidably engaged by one semicylindrical half of the igniter end portion, the other leg having an arcuately formed portion coextending with and having its concave surface facing said straight leg portion and being adapted to receive the other semicylindrical half of the igniter end portion, and said base member having a perforation therein between said legs adapted to receive the polarizing fin, thereby to limit rotational and axial movement of the igniter in the device.

5 2. The device claimed in claim 1 in which the radius of said arcuately formed portion of said other leg is slightly less than the radius of the semicylindrical igniter end portion of an igniter it is to receive.
